PREPARATION OF SUBSTITUTED BIS-AMINOPHENYL ETHYLENE GLYCOLS

Milton J. Allen, Baltimore, Md., assignor to the United States of America as represented by the Administrator, Federal Security Agency

No Drawing. Application November 5, 1948,
Serial No. 58,630

4 Claims. (Cl. 204—77)

(Granted under the act of March 3, 1883, as amended April 30, 1928; 370 O. G. 757)

1

The invention described herein may be manufactured and used by or for the Government of the United States for governmental purposes without the payment to me of any royalty thereon in accordance with the provisions of the act of April 30, 1928 (ch. 460, 45 Stat. L. 467).

This invention relates to the production of pinacols, and, more particularly, relates to the production of pinacols by electrolytic bimolecular reduction. Still more particularly, this invention relates to the production of α, β -substituted bis-aminophenyl ethylene glycols by the electrolytic bimolecular reduction of compounds containing the aminophenyl ketone nucleus.

Accordingly, this invention has for an object the production of aminoaryl pinacols by the electrolytic bimolecular reduction of aminophenyl ketone compounds. Another object of this invention is to provide electrolytic reduction conditions for the production of α, β -substituted bis-aminophenyl ethylene glycols in a very high yield. Still another object of this invention is to provide a process for the preparation of new compounds having anti-estrogenic properties. Another object is the preparation of compounds used as intermediates in the preparation of therapeutically active compounds.

The foregoing and other objects hereinafter apparent are accomplished in accordance with this invention wherein bis-aminophenyl pinacols are produced by subjecting a solution of a compound containing the aminophenyl ketone nucleus to electrolytic reduction. In one preferred embodiment, para-amino acetophenone is subjected, in a hydrochloric acid solution, to electrolytic reduction at a temperature not higher than 40° C. and at a substantially constant overvoltage above the decomposition potential of para-amino acetophenone but below the overvoltage at which substantial quantities of molecular hydrogen are liberated.

While it is not intended to limit this invention by any theory of operation, it is thought that the following chemical equation expresses the course of the reaction:

In the equation, "R" may be alkyl, aryl or the like. In the acidic solution employed, the pinacol

2

is first secured in the form of a salt with the selected acid, for example, hydrochloric acid yields the hydrochloride salt. After formation of the pinacol dihydrochloride by electrolytic reduction, the free base is liberated by neutralization.

Suitable compounds for pinacol formation in accordance with this invention include compounds containing the aminophenyl ketone nucleus, such as, for example, the ortho, meta and para amino acetophenones, propiophenones, butyrophenones, and other amino arylalkyl ketones, as well as the amino diaryl ketones such as, for example, bis-(aminophenyl) ketones and similar diaryl ketones. Preferably, para-aminoacetophenone is employed for electrolytic bimolecular reduction in accordance with this invention since there results a very high yield of the corresponding pinacol.

20 The electrolytic production of pinacols in accordance with this invention is preferably carried out in an acidic solution, whereby transmission of the electric current and solubility of the selected aminophenyl ketone are both promoted. 25 Acidic substances capable of conducting electric current readily may be used, such as, for example, sulfuric acid, acetic acid, formic acid, and preferably hydrochloric acid. Mixtures of acids or acids and ionizable salts may be employed.

In carrying out the electrolytic bimolecular reduction to form a pinacol, it has been found that the employment of a diaphragm type electrolytic cell is preferable, inasmuch as the bimolecular reduction takes place in solution adjacent the cathode and it is desirable to minimize physical contact of the reduced compound with the anode to prevent reoxidation of the product. Any suitable semi-porous or semi-permeable membrane can be employed to provide a diaphragm such as, for example, sintered glass, porous porcelain, and preferably, a regenerated cellulose foil, such as that sold to the trade under the name of "Visking" (normally employed as a sausage-casing material). Obviously, in the electrolytic reduction, the anode is surrounded with diluted acid at the commencement of the reaction and the acidic solution of the aminophenyl ketone is placed in the cathode chamber. A mercury cathode and a carbon or preferably a platinum anode can be employed, although other electrodes may be satisfactory.

In carrying out the production of pinacols in accordance with this invention, it has been found that the bimolecular electrolytic reduction should

be carried out at a substantially constant overvoltage above the decomposition potential of the compound being reduced but below the overvoltage at which substantial quantities of molecular hydrogen are liberated. It has been found that an overvoltage of from 1.2 to 1.6 volts may be employed and preferably, the overvoltage is maintained at about 1.5 volts for para-amino acetophenone. Other selected keto-aniline compounds require an overvoltage as high as 2 volts or higher. In general, it has been found that an applied voltage between 4 and 7 volts provides the desired overvoltage, taking into consideration the cell resistance and other electrolysis factors. At an overvoltage which is too low, pinacol formation is repressed and the yields are low, while at a high overvoltage, molecular hydrogen is liberated in great quantities at the cathode so as to retard the desired electrolytic reduction.

During electrolysis, the acidic solution being electrolyzed is maintained at a temperature between about 15° C. and about 40° C., preferably between the more restricted temperature range of 20° C. and 25° C. At temperatures much higher than 40° C., the amino acetophenone or other aminophenyl ketone is largely reduced to an alcohol rather than being reduced bimolecularly to the desired pinacol. At temperatures greatly below 15° C., current transmission and solubility difficulties may be encountered. During the course of electrolytic bimolecular reduction, the current density varies considerably, and it has been found that the constant overvoltage impressed upon the cell forms a reliable means of controlling the pinacol formation.

In carrying out the electrolytic bimolecular reduction of para-aminoacetophenone, or other compounds containing the aminophenyl ketone group, to produce the corresponding pinacols, the selected keto compound is first dissolved in a solution of a conductive acid such as hydrochloric acid, diluted with water. Generally, the keto compound is dissolved to make a solution containing on a molar basis, from one-half to one and one-half mols. per liter and preferably about one mol. per liter. The acid, such as for example, hydrochloric acid, is diluted to make a 5 to 15% solution. The anode chamber is then filled with acid solution and the cathode chamber is filled with the acidic solution of aminoacetophenone or other aminophenyl ketones. The electrolytic cell is provided with a mercury cathode and preferably a platinum anode and is further provided with heating and cooling means to maintain the temperature at about 15° C. to 40° C. The electrolytic cell is also provided with means for maintaining a substantially constant overvoltage of, for example, 1.2 to 2 volts. The electrolysis is begun and continues until the electrolytic reduction is terminated; as is usually indicated by strong hydrogen evolution at the mercury cathode. After completion of the reduction, the catholyte containing the desired pinacol is treated to remove excess water and hydrochloric acid, as by evaporation to dryness, and then extracted with anhydrous ethanol containing ethyl acetate for the purpose of removing by-products and unconverted raw material. The purified residue, namely the hydrochloride or other acid salt of the desired pinacol, is then dissolved in water and made slightly alkaline with caustic soda, ammonia, or other alkali to liberate the free base. Upon treatment with alkali, a precipitate is formed which is filtered off, washed with water and recrystallized from acetone, ethyl-

ene glycol monoethyl ether, or other suitable solvents. By this purification, the desired pinacol is recovered in a high yield.

The following examples illustrate this invention but are not to be considered as restricting the invention thereto:

EXAMPLE I

Preparation of bis (para-aminophenyl) methyl ethylene glycol dihydrochloride and its free base

Six grams of para-aminoacetophenone are dissolved in 300 cc. of 5% hydrochloric acid and placed in the mercury cathode chamber of a dia-phragm-type electrolytic cell provided with means for heating and cooling the same. The compartments are separated into an anode chamber and a cathode chamber by a permeable diaphragm which in this example was a regenerated cellulose foil sold to the trade as "Visking" sausage skin. The anode chamber contains a platinum anode and a 5% solution of hydrochloric acid. The current is started and the electrolytic reduction proceeds at an overvoltage of 1.2 volts. The initial applied voltage is 4.6 volts and the initial current flowing through the cell is 1.5 amperes. After about one hour, the contents of the cathode chamber are removed and evaporated to dryness under vacuum at room temperature whereby hydrochloric acid and water are removed. The residue remaining is triturated with about 25 to 30 ml. of anhydrous ethanol. To this is then added an equal amount of ethyl acetate, the resulting mixture is chilled and the undissolved portion filtered off. The resulting residue is then again washed with a cold mixture of equal parts anhydrous ethanol and ethyl acetate. After drying, a yield of bis-(para-aminophenyl) methyl ethylene glycol dihydrochloride in an amount of 16% of the theoretically possible yield is obtained. The product was a light yellow powder, decomposing at about 230° C. By combining the wash liquids employed above with the mother liquor and evaporating to dryness, a byproduct identified as alpha-para-aminophenyl ethanol hydrochloride may be obtained. The free base, bis-(para-aminophenyl) methyl ethylene glycol, is prepared by dissolving the dihydrochloride in water, adding sufficient sodium hydroxide to make the solution slightly alkaline, whereby a precipitate is formed, filtering off the precipitate and washing the same with water to remove the sodium chloride formed. The precipitate is recrystallized from acetone to produce bis-(para-aminophenyl) methyl ethylene glycol having a melting point of 248-249° C., in the form of white platelets.

EXAMPLE II

Eighty-one grams of para-aminoacetophenone is dissolved in 600 ml. of 13.5% hydrochloric acid and subjected to electrolytic bimolecular reduction in the electrolytic cell described in Example I at an overvoltage of 1.5 volts while maintaining the catholyte temperature within the range of 20° C. to 30° C. The cell is provided with means for maintaining a constant overvoltage and the initial applied voltage is 4.5 volts yielding an initial cell current of 3.2 amperes. After about six hours, the completion of the reduction is evidenced by the copious evolution of hydrogen from the mercury cathode surface and the catholyte containing the desired product is evaporated to dryness under vacuum at room temperature, extracted with anhydrous ethanol and ethyl acetate as described in Example I, and purified in a

manner similar to that described in Example I. Bis-(para-aminophenyl) methyl ethylene glycol dihydrochloride is recovered in a yield that is 65% of that theoretically possible.

By neutralizing a solution of the hydrochloride above prepared and recrystallizing from ethyl Cellosolve (the mono-ethyl ether of ethylene glycol), bis-(para-aminophenyl) methyl ethylene glycol having a melting point of 248-249° C. is recovered in the form of white platelets.

From the foregoing, it will be apparent that this invention provides a simple process for the electrolytic bimolecular reduction of para-aminoacetophenone or other aminophenyl ketones to form the corresponding alpha beta disubstituted pinacols. Yields of 65% of the theoretical have been obtained. The new pinacols produced have anti-estrogenic properties and are themselves useful as intermediates in the production of compounds having estrogenic activity.

Various changes may be made in the invention without departing from the spirit and scope thereof.

What is claimed is:

1. In a process for the production of alpha, beta substituted bis-(aminophenyl) ethylene glycols the step which comprises subjecting an acidic solution of a compound containing the aminophenyl ketone nucleus to electrolytic reduction at a substantially constant cathode overvoltage above the decomposition potential of the compound being reduced but below the overvoltage at which substantial quantities of molecular hydrogen are liberated.

2. The process of claim 1 wherein the overvoltage is maintained between 1.2 and 2.0 volts.

3. In a process for the production of a bis-(para-aminophenyl) methyl ethylene glycol the step which comprises subjecting an approximately

one molar solution of para-aminoacetophenone in hydrochloric acid to electrolytic bimolecular reduction at a temperature between 15° C. and 40° C. and at a substantially constant cathode overvoltage between 1.2 to 1.6 volts.

4. In a process for the production of bis-(para-aminophenyl) methyl ethylene glycol the step which comprises subjecting a para-amino-acetophenone solution of one molar concentration in 10 13.5% hydrochloric acid to electrolysis at a substantially constant cathode overvoltage of about 1.5 volts, and an initial applied voltage of about 4.5 volts, while employing a cellophane-shrouded platinum anode, a mercury cathode and maintaining the electrolyte temperature at 20° C.-25° C., and continuing said electrolysis until bis-(para-aminophenyl) methyl ethylene glycol hydrochloride is formed.
